UNITED STATES PATENT OFFICE.

FREDERICK E. DRISKILL, OF BERWICK, LOUISIANA.

DIRECTION-INDICATOR.

1,172,960.

Specification of Letters Patent. Patented Feb. 22, 1916.

Application filed April 16, 1915. Serial No. 21,791.

To all whom it may concern:

Be it known that I, FREDERICK E. DRISKILL, a citizen of the United States, residing at Berwick, in St. Mary parish and State 5 of Louisiana, have invented certain new and useful Improvements in Direction-Indicators; and I do hereby declare the following to be a full, clear, and exact description of the invention, such as will enable others 10 skilled in the art to which it appertains to make and use the same.

This invention relates to new and useful improvements in direction indicators, and the principal object of the invention is to 15 provide a device for indicating the direction to be taken by a motor vehicle.

Another object of the invention is to provide a device which is readily attachable to motor vehicles of the usual construction 20 without necessitating the changing of the construction in any manner.

A further object of the invention is to provide a simple and efficient device which may be readily controlled from the steering 25 post of the vehicle.

Still another object of the invention is to provide a novel means for operating the several parts.

With these and other objects in view, the 20 invention consists in the novel combination and arrangement of parts which will be fully set forth in the following specification and accompanying drawings, in which—

25 Figure 1 is a perspective view of the mechanism showing the same ready for use. Fig. 2 is a sectional view through one of the forward lamps. Fig. 3 is a front view in elevation of the lamp. Fig. 4 is a front 40 view showing the lamp in its reversed position, and Fig. 5 is a detail view of the reflector supporting arm.

Referring now to the drawings by characters of reference the numeral designates 45 as an entirety the lamp casing of one of the forward lamps comprising a cylindrical body 2 which is open at each end. This body is formed intermediate its ends with the diametrically opposite ventilating hoods 50 3 and carried in the body is the lens 4, while the rear end is provided with the glass panel 5, having suitable designating characters 6, painted or otherwise formed thereon. It will be evident that when the 55 lamp is in either of its positions the ventilating hood 3 will coöperate in causing a

draft therethrough, so that the flame from the burner which will be more fully hereinafter described may be properly furnished with the necessary oxygen.

60 The lamp casing 2 is provided at diametrically opposite points at an angle of ninety degrees from the center of the hoods 3 with the tubular extensions 6 which are arranged to receive the tubular portions 7 which are 65 formed at their outer ends with rectangular extensions 8. These rectangular extensions 8 project through rectangular apertures formed in the upper ends of the lamp brackets 9 and both the portions 7 and the extension 8 are hollow to receive the pipe 10 through which the illuminating gas passes. This pipe extends through a suitable ear 11 70 formed on the supporting ring 12 of the reflector 13 and these ears 11 are formed with the extensions 7, so that the reflector is held stationary regardless of the position of the lamp casing. It will thus be seen that the lamp casing can be reversed so that the 75 characters on the screen or panel 5 may be 80 easily read.

In order to provide a reversing means for the casing, the gear wheel 14 is provided and is secured to one of the extensions 6 and meshing with this gear wheel is a suitable ar- 85 cuate rack 15 which is pivotally mounted at 16 to a suitable support and is provided with the arms 17, the lower end of which is secured to an operating rod as at 18. A suitable retractile coil spring 19 is connected to 90 the arm 17 and the opposite end of the coil spring is secured as at 20 to a rigid support so that the lamp casing will be automatically returned to its normal position after the same has been released. In order to 95 illuminate the interior of the casing the pipe 10 is bent downwardly as at 21 and passes through an opening 22 formed in the lower edge of the reflector and is then bent upwardly as at 23 and carries the tip 24. It 100 will thus be seen that the flame is disposed centrally of the reflector 13 and it will remain in that position regardless of the position of the casing 2.

Secured to each side of the vehicle and ar- 105 ranged to operate the lever 17 hereinbefore referred to is a suitable rod 25 which is provided intermediate its end with suitable up- standing pins 26. These pins 26 are ar- 110 ranged to be engaged by the hook ends 27 of the arm 28 which is pivoted as at 29 centrally of the ends and to the frame of the

vehicle. A suitable depending ear 30 is formed on the arm 28 near one end of its ends and pivotally connected thereto is the arm 31 of the bell crank designated generally by the numeral 32. The opposite arm 33 of said bell crank has pivotally connected thereto the rod 34 which extends upwardly parallel to the steering post of the vehicle and terminates in the hand hold 35. This 10 rod is provided with a suitable lug or dog 36 which is arranged to engage the teeth 37 of the bar 38 which is rigidly secured to the steering post so that when the bar is moved, it may be held in adjusted position. Each 15 of the bars 25 is provided at its rear end with a suitable hinge joint 39 and carries the spring 40, the use of which will appear as the description proceeds.

Hinged to the hinge joints 39 are the extensions 41 having enlargements 42 formed intermediate their ends. Extending downwardly from the frame of the vehicle are the brackets 43 carrying at the lower ends, the roller 44 which are arranged to engage the faces of the enlargements 42 when the bars 25 are moved forwardly so as to cause the dogs 45 to engage the coöperating dogs to operate the rear light as will be more fully hereinafter described.

30 Coöperating with the dogs 45 are the latch dogs 46 which are carried on the slidable rods 47, which rods are mounted in the eyes 48 carried by the frame 49. The rear ends of these rods are pivoted as at 50 to the cross arms 51, which cross arms are formed on the longitudinally extending bars 52, the rear end of which is formed with the arcuate rack 53, which meshes with a suitable gear wheel 54 mounted on the shaft 55 carrying the light 56. The opposite end of the arm 52 is formed with a suitable eye 57 to which the ends of the retractile coil spring 58 are connected. The opposite ends of these springs are secured as at 59 to the side bars 45 of the frame 49 and it will thus be seen that the bar 52 will be normally held in a position shown in Fig. 1.

It will be apparent from the foregoing that in use upon exerting upward pull on 50 the handle 35 the bell crank 32 will be moved so as to swing the bar so that the hook end 27 thereof on the left hand side will engage the lug 26 carried by the bar 25 on the left hand side of the vehicle. This movement

will actuate the lever 17 and cause the light 55 casing on the left side of the vehicle to turn over so as to expose the characters on the screen or panel 5 thereof. Simultaneously with this movement the enlargement 42 on the extension 41 will engage the roller 44 60 and force the free end of the extension downwardly so that the latch dog 45 will engage the latch dog 46 on the left side of the vehicle and thereby exert pull on the rod 47 so that the arm 51 will be swung to the 65 left, thereby exposing the panel L of the lamp 56. Upon releasing the handle 35 it will be evident that the springs 19 and 58 will return the several parts to their normal positions and the spring 40 will lift the 70 member 41 free from engagement with the latch dogs 46. Upon pushing downwardly on the handle 35 it will be apparent that the same operation will be gone through except that the bar 45 on the right hand side of the 75 vehicle will be operated instead of the bar on the left hand side, and thereby the right hand signal will be operated. In this way it will be clearly evident that directions may be given as to the intentions of the driver of 80 a vehicle and thereby eliminate many of the accidents accompanying the use of motor vehicles.

While in the foregoing there has been shown and described the preferred embodiment of this invention, it is to be understood that such changes may be made in the combination and arrangement of parts as will fall within the spirit and scope of the appended claim.

What is claimed is:

A device of the character described including a frame, rods slidable on said frame, a lever pivoted to the frame, arms on the lever and connected to the rods, indicating 95 means actuated by the lever, latch dogs at the forward ends of the rods, springs to hold the lever in longitudinal alinement with the frame and independently movable operating bars provided with latch dogs arranged to 100 engage the latch dogs on the rods to control the movement of the indicator.

In testimony whereof I affix my signature in presence of two witnesses.

FREDERICK E. DRISKILL.
